US00D754346S

(12) **United States Design Patent**
Pimenta et al.

(10) **Patent No.:** **US D754,346 S**
(45) **Date of Patent:** **** Apr. 19, 2016**

(54) **SPINAL FUSION IMPLANT**

(71) Applicant: **NuVasive, Inc.**, San Diego, CA (US)

(72) Inventors: **Luiz Pimenta**, Sao Paulo (BR); **Patrick Miles**, San Diego, CA (US); **Benjamin VerHage**, New York, NY (US); **Nathan Lovell**, Oceanside, CA (US)

(73) Assignee: **NuVasive, Inc.**, San Diego, CA (US)

(**) Term: **14 Years**

(21) Appl. No.: **29/479,802**

(22) Filed: **Jan. 20, 2014**

Related U.S. Application Data

(63) Continuation of application No. 12/396,458, filed on Mar. 2, 2009, now abandoned.

(51) **LOC (10) Cl.** **24-02**

(52) **U.S. Cl.**

USPC **D24/155**

(58) **Field of Classification Search**

(57) **CLAIM**

The ornamental design for a spinal fusion implant, substantially as shown and described.

DESCRIPTION

FIG. 1 is a perspective view of a spinal fusion implant showing our new design;

FIG. 2 is a top view of the spinal fusion implant of FIG. 1; FIG. 3 is a first side view of the spinal fusion implant of FIG. 1

FIG. 4 is a first end view of the spinal fusion implant of FIG. 1; and,

FIG. 5 is a second side view of the spinal fusion implant of FIG. 1.

1 Claim, 3 Drawing Sheets
